UNITED STATES PATENT OFFICE.

DEMING JARVES, OF DETROIT, MICHIGAN.

RETORT.

SPECIFICATION forming part of Letters Patent No. 317,135, dated May 5, 1885.

Application filed February 5, 1885. (No model.)

To all whom it may concern:

Be it known that I, DEMING JARVES, of Detroit, in the county of Wayne and State of Michigan, have invented new and useful Improvements in Retorts; and I do hereby declare that the following is a full, clear, and exact description thereof, reference being had to the accompanying drawings, which form a part of this specification.

10 This invention relates to certain new and useful improvements in the construction of retorts in which destructive distillation is carried on by means of applied heat.

The invention consists in so constructing a 15 retort that when used in a vertical position, as in the manufacture of bone-black by the destructive distillation of bones, the mass to be acted upon by the heat is prevented from dropping down below the point where there 20 is no heat applied, in the peculiar construction of the retort, by means of which the gases are retained and discharged, and in the peculiar construction and operation of the various parts, as more fully hereinafter described.

25 Figure 1 is a vertical central section of my improved retort. Fig. 2 is a cross-section of the same on the line X X in Fig. 1. Fig. 3 is a plan view of the slide-gate. Fig. 4 is a detail showing the manner of securing the end 30 of the slideway to prevent the escape of gas at that point.

In the accompanying drawings, which form a part of this specification, A represents a 35 rectangular retort having lugs *a* cast or otherwise secured thereto, which, when the retort is in use, rest upon the floor of the kiln, the contracted mouth *b* projecting below the floor and terminating in a thickened rim, *c*, in which there is formed an annular recess, 40 *d*. There are also cast or formed upon the outer walls of said retort other lugs, *e*, which support the roof of the kiln, the upper end of the retort projecting above such roof, and the roof rises and falls with the elongation and

45 shortening under the expansion and contraction of the retort. At this end of the retort one side of the retort is contracted, thereby providing a comparatively small mouth, *d'*, upon which a cover, B, has to be luted and sealed in any of the known ways. Around the 50 upper end of this mouth, which is thickened

for that purpose, there is formed an annular recess like that described as surrounding the opposite or discharge end of the retort, and the covers of both ends are alike, having an 55 annular recess, *h*, formed upon their inner faces, so that when in place a flange surrounding the annular recess in the covers will fit into the similar recess in the ends of the retort. This contraction of the upper end enables me to form a discharge-pipe, C, for the 60 gas, projecting from the larger section of the body directly vertical, communicating with the retort-chamber, as shown, without, as heretofore, the necessity of making an L-connection 65 through the side wall of such retort.

At or about the point where the contraction of the lower end of the retort commences there is formed a rectangular box, D, opening at one end into the side wall of such retort, and which forms a guide for the slide E, which is adapted to be projected into and across the interior of the retort, and when thus projected to rest upon a lug or ledge, *i*, formed on the inner face of the wall opposite the 70 opening in the opposite wall, through which the slide is projected. This slide forms a removable bottom for that portion of the retort which is subjected to the action of the heat in the kiln. The projecting end of the slide-box 75 has a cover, *k*, bolted thereon, with a central hole therein, through which a removable handle, F, is inserted to operate the slide, which latter has a hole, *l*, near its end, to engage with a lug or hook, *m*, on the handle. At 80 attached to the outside of this cover *k* is a hollow stud, *n*, the opening through which is coincident with the opening in the cover, and this stud is threaded to engage with a screw-cap, *o*. To operate the slide this cap is removed and the handle inserted through the hollow stud. The handle is then withdrawn 85 and the cap replaced to prevent the escape of gas at this point.

In practice these retorts are set in benches, 90 with their lower ends projecting through the floor of a proper kiln, and their upper ends projecting through the roof of said kiln. The cover is luted and secured to the lower or discharge end, and the slide projected within the 95 retort to form a false bottom. The upper cover being removed, the retort is filled with bone,

for instance, when the cover is replaced, luted, and secured. The gases are prevented from escaping by the means described, except through the discharge-pipe C, which conveys them to 5 the point where they are utilized—for instance, in making ammonia. When the process of destructive distillation has been carried on sufficiently long, the lower cover is removed and the slide withdrawn, when the results in the form of ~~one~~-black will be discharged through the lower end of the retort, which is contracted to form a discharge-mouth, and to avoid the necessity of luting so large a joint, as would be necessary had not 15 such contraction been made. The contraction for the lower end is equal on all the sides of the retort, thereby giving a central discharge for the contents without anything to interrupt such free discharge.

20 One object of contracting the upper end of the retort is to lessen the amount of luting to be done, and the contraction being from one side only gives room for the discharge-pipe for the gases to project vertically from the 25 body of the retort, thereby avoiding the L-shaped connection for the same purpose, in

which extraneous matter will collect, requiring to be frequently cleaned out.

I am aware of the Patent No. 171,813, and make no claim to anything shown therein as 30 forming part of my invention.

What I claim as my invention is—

1. A retort having means for supporting it upon the floor of a kiln, and for supporting the roof of said kiln, centrally contracted to 35 form a discharge-mouth at its lower end, eccentrically contracted at its upper end, and having a vertical gas-discharge pipe by the side of the contracted upper end, substantially as and for the purposes described. 40

2. A retort having an opening in its side wall communicating with a rectangular open-ended box, and having an interior lug or ledge, in combination with a slide-gate, a detachable handle for operating said slide-gate, and means, 45 as described, for closing the outer end of such slide-inclosing box against escaping gas, substantially as and for the purposes specified.
